EXPANSIBLE LINK CHAIN FOR A WRIST-BAND OR SIMILAR ARTICLE

Alfred Pinson, Stamford, Conn., assignor to Apex Accessories Co., Inc., Greenwich, Conn.

Application February 28, 1952, Serial No. 18,706

Term of patent 14 years

(Cl. D45—4)

To all whom it may concern:

Be it known that I, Alfred Pinson, a citizen of the United States, residing at Stamford, in Fairfield County, State of Connecticut, have invented a new, original, and ornamental Design for an Expansible Link Chain for a Wristband or Similar Article, of which the following is a specification, reference being had to the accompanying drawing forming part thereof.

Fig. 1 is a top plan view of an expansible link chain for a wristband or similar article, showing my new design, portions of the conventional bottom links being visible between the top links and shown in broken lines; and

Fig. 2 is a side elevational view thereof, the

conventional bottom links being shown in broken lines.

I claim:

The ornamental design for an expansible link chain for a wristband or similar article, as shown and described.

ALFRED PINSON.
